United States Patent

Des. 241,055
Patented Aug. 17, 1976

241,055

SPINNING TOP

Robert C. Wohlstrom, 25231 Romera Place,
El Toro, Calif. 92630

Filed Nov. 27, 1974, Ser. No. 527,898

Term of patent 14 years

Int. Cl. D21—02

U.S. Cl. D34—15 AH

FIG. 1 is a top perspective view of a spinning top showing my new design;

FIG. 2 is a bottom plan view thereof;

FIG. 3 is a side elevational view thereof; and

FIG. 4 is a top perspective view of a modified form of the design shown in FIG. 1, the unshown sides being the same as FIGS. 2 and 3.

I claim:

The ornamental design for a spinning top, substantially as shown and described.
